UNITED STATES PATENT OFFICE.

ELIAS T. GOLDBERG, OF BRIDGEPORT, CONNECTICUT.

ARTIFICIAL TOOTH.

1,310,237.

Specification of Letters Patent. Patented July 15, 1919.

Application filed October 18, 1918. Serial No. 258,362.

To all whom it may concern:

Be it known that I, ELIAS T. GOLDBERG, a citizen of the United States, residing at the city of Bridgeport, county of Fairfield, 5 State of Connecticut, have invented certain new and useful Improvements in Artificial Teeth; and I do declare the following to be a full, clear, and exact description of the invention, such as will enable others 10 skilled in the art to which it appertains to make and use the same.

This invention relates to certain new and useful improvements in artificial teeth and more particularly to an improved means for 15 securing or anchoring replaceable porcelain facings to metal or other backings.

It has been proposed to unite the porcelain facings to their backings by a tongue and groove or dovetail connection but this 20 method has thus far proven impractical for the reason that the undercut groove in the porcelain would warp and become misshapen as a result of the irregular shrinkage during the baking of the porcelain. 25 This lack of uniformity of the porcelain groove rendered it exceedingly difficult to fit a standard backing, and often the metal tongue would fit so loosely that the large amount of cement necessitated would soon 30 crumble under constant use and thereby be useless.

It is the aim and primary object of this invention to overcome this difficulty by providing a metal lock between the porcelain 35 and its backing.

The invention consists in securing a slotted metal lock member to the porcelain during the manufacture thereof, either by shrinking the porcelain about the metal 40 when baking the facing or by a cementitious binder, said lock member being fitted in a groove in the back face of the porcelain and of such shape as to receive the metal tongue of the backing.

45 In the drawing—

Figure 1 is a front elevation of a set of teeth in process of construction, certain facings having been omitted;

Fig. 2 is a rear elevation of the improved 50 porcelain facing;

Fig. 3 is a vertical section on line 3—3 of Fig. 1;

Fig. 4 is a horizontal section on line 4—4 of Fig. 1;

55 Fig. 5 is a vertical section through a modi-

fied form of facing especially adapted for a back tooth; and

Figs. 6 and 7 are end elevations of modified forms of the lock member.

Referring more in detail to the drawing, 60 the porcelain facing 1 is formed with an undercut groove 2 in its back face, which groove preferably opens through one end of the porcelain body in the form of a flared gateway, as illustrated in Figs. 2 65 and 3. A metal lock member 3 is then inserted within the groove 2 with its edges engaging beneath the undercut or overhanging sides of the groove. This lock plate or member 3 is secured in position by 70 either relying on the shrinkage of the porcelain during the baking process to firmly unite the plate and porcelain, or by initially baking the porcelain and then inserting the lock member within the undercut portion 75 with an intermediate application of suitable cement.

The outer end of the lock plate is longitudinally slotted, as at 4, to receive and embrace the neck or shank of a hook-shaped, 80 headed stud 5 projecting from the metal backing 6. The head of this stud 5 substantially conforms to the pocket thus defined by groove 2 and lock plate 3 to afford a tight fit which may be maintained by a 85 cementitious binder.

By the provision of the metal lock plate, metal will then fit metal and the certainty of a tight fit and joint is practically assured. The characteristics of the metal 90 from which the lock plates are constructed are such that the same will not fuse or be affected by the heat required for the baking of the porcelain. The lock plate is preferably half round or half tubular in cross 95 section, having one side opened, but other shapes may be employed as indicated in Figs. 6 and 7 wherein the lock members 7 and 8 are tubular and of semi-cylindrical or polygonal cross section.

Fig. 5 illustrates a back tooth in which a wide opening, constituting the gateway for the lock plate member, is provided. The cement binder would therefore be more exposed to outside influences but to avoid such 105 exposure the backing 6 is downturned across the gateway to form a closure lip 9.

In constructing a set of teeth, the metal backings are assembled edge to edge and the gold or other reinforcement 10 is then ap. 110

plied thereto. The undercut slots or grooves in the porcelain facings are filled with a cementitious substance and the entrance gates positioned relative to the headed anchoring studs for being slid into position.

What is claimed is:

1. An artificial tooth comprising a porcelain facing formed in its back face with a substantially dovetailed groove, and a lock plate bent from sheet metal and having its side edges inturned to engage beneath the undercut walls of the groove and its inner end abutting the end wall of the groove, the outer end of said lock plate being formed with a slot narrower than the space between the outer edges of the groove.
2. An artificial tooth comprising a porcelain facing having a groove in its back face, and a metal lock plate convexing outwardly to close the space intervening the outer edges of the groove and having its edge portions

seating on the bottom of the groove, said plate spaced outwardly from the bottom of the groove to receive the head of a mounting stud between said groove bottom and the 25 plate.

3. An artificial tooth comprising a porcelain facing formed with a groove in its back face opening in a wide gateway through one end thereof, the sides of the groove being undercut, a metal lock plate inserted in the groove with its edges engaging in the undercut sides thereof, said plate being slotted adjacent the entrance gate of the groove, and a metal backing having a headed 35 stud fitting the groove beneath the plate with its shank disposed in the slot of said plate, the outer end of the backing being downturned to form a closure lip for the gateway of the facing groove. 40

In testimony whereof I affix my signature.
ELIAS T. GOLDBERG.
